UNITED STATES PATENT OFFICE.

HENRY SIMPSON, OF LIVERPOOL, ENGLAND.

MARINE BRAKE.

SPECIFICATION forming part of Letters Patent No. 703,487, dated July 1, 1902.

Application filed April 15, 1902. Serial No. 102,992. (No model.)

To all whom it may concern:

Be it known that I, HENRY SIMPSON, a subject of the King of Great Britain, residing in Liverpool, in the county of Lancaster, England, have invented certain new and useful Improvements in Apparatus for Arresting the Motion of Navigable Vessels, of which the following is a specification.

This invention comprises certain improvements in apparatus for arresting the motion of navigable vessels of the kind described in the specification forming part of Letters Patent No. 662,829, granted to me and dated November 27, 1900.

15 My object in the present invention is to adapt the apparatus for very high speed vessels, especially those propelled by engines of the turbine type, where the excessive speed and comparatively inefficient means for propelling astern make the need of arresting apparatus more urgent and require it to be much more powerful.

In order to increase the effectiveness of the arresters, I modify the construction according to my present invention as follows: I fit a series of arresters one behind the other on each side of the vessel, each two of symmetrically-disposed pairs being adapted to be operated simultaneously, while the various pairs 30 may be operated in succession. I increase the effective depth of each of the arresters of a pair by placing one-half of the arrester on each side of a deck or stringer. I increase the retarding effect by providing for a thorough 35 passage of water through the cavity in which the arrester is housed, and I render the action more certain and definite by articulating the arrester to the door which normally closes the compartment, so that the latter is 40 opened when the arrester is turned to the arresting position. I also effect certain improvements in matters of detail, which will be more fully described hereinafter.

I have illustrated my invention in the accompanying drawings, in which—

Figure I is an elevation. Fig. II is a plan, the ship being in section on the plane X Y; Fig. III, a plan, the upper half being in section, as in Fig. II, and the lower half being 50 a plan of the deck on which the operating

means are placed; and Fig. IV, a view of a detail to a larger scale.

The arresters 1 are hollow structures mounted on spindles 2', which spindles are operated by means of cranks 3, connecting-rods 4, cross-heads 5, and double-acting hydraulic or steam cylinders 6. The ship 7 is so constructed as to form a series of cavities, in which the arresters are located. The cavities, however, are larger than they would require to be merely to accommodate the arresters, so that when the latter are in operation the water can flow through the cavity and around the back of the arrester, as shown in the case of the rear starboard arrester in Fig. II, which flow by preventing the cavity being merely filled with dead water considerably increases the resistance to motion. The rear of each cavity is closed by the arrester when the latter is in normal position, and the forward end is closed by a door 8, 70 suitably hinged and which may be hollow to give buoyancy. The ship is strengthened by bars 9, which again are strengthened by the junction-plates 10, which unite the bars to the deck. Each door has a projecting portion 75 which when the door is closed abuts against the bars, and the arresters have a similar projection, which is adapted, as shown, to abut against the projection on the doors. In order to insure that the doors shall open when 80 the arresters are opened, the two are articulated together as follows: A slotted bar 12 is attached to the door, and a pin 13, engaging in the said slot, is attached to the arrester. The slot is so shaped that the arrester and 85 door are so articulated together that they open and close together.

The construction of the spindle 2', on which the two parts of the arrester are mounted, is shown in Fig. IV, from which it will be 90 seen that the spindle is made up of two parts 2 and 2'. The lower part of 2 enters a recess in the upper part of 2' in such manner that while there can be but small relative rotation between the two parts the joint is free enough 95 to permit of considerable want of alignment.

It will be seen that the longitudinal division of the cavities by the deck and the provision of cross-bars connected by junction-plates to the deck not only very considerably 100

strengthens the hull, but also admits of the fitting of twin arresters, operated by the one operating means and yet articulated together by means which permit departure from true alinement.

The operating means, such as the hydraulic cylinders, may be controlled by any suitable and well-known devices. In some cases special means—such, for example, as are used in steam steering-gear—may be used, so that the amount of opening of the arresters may be regulated, in which case the latter may be used for steering the ship in event of disassembly of the rudder or in addition to the rudder. The controlling means may also be adapted to open all the arresters simultaneously or to open them in pairs in succession, as may be desired.

In some cases it may be desirable to carry the arresters so that in plan the apex of the triangle may point forward instead of aft, as shown.

Having now fully described my invention, what I claim, and desire to secure by Letters Patent, is—

1. In combination; a ship in the hull of which is formed a series of cavities symmetrically disposed in pairs on opposite sides of the center line; a series of arresters pivotally located in the said cavities and leaving, when in arresting position, passage-ways for the water to flow through the cavities and around the arresters; a series of hinged doors; means for articulating the doors to the arresters so that they open and close therewith and are held open thereby; and means for operating the arresters; substantially as described and illustrated.

2. In combination; a ship in the hull of which is formed a series of cavities symmetrically disposed in pairs on opposite sides of the center line, each cavity being divided longitudinally into two parts by one of the ship's

decks and strengthened by bars and junction- 45 plates; a series of twin arresters pivotally located in the said cavities and leaving, when in arresting position, passage-ways for the water to flow through the cavities and around the arresters; a series of hinged double doors; means for articulating the doors to the arresters so that they open and close therewith and are held open thereby; and means for operating the arresters; substantially as described and illustrated.

3. In combination; the ship's hull with the 55 divided cavities; the twin arresters; the hinged doors; the means for operating the arresters; and the double spindle for the twin arresters, consisting of two parts jointed together so as to prevent relative rotary move- 60 ment while permitting departure from absolute alinement; substantially as described and illustrated.

4. In combination; the ship's hull with the 65 cavities and bars; the doors having projec- tions adapted to abut against the said bars; the arresters having projections adapted to abut against the projections on the doors; means for articulating the doors to the arresters; and means for operating the arresters; 70 substantially as described and illustrated.

5. In combination; the ship's hull with the 75 cavities; the arresters; the doors; the means for operating the arresters; and the means for articulating the arresters to the doors, consisting of slotted bars attached to the doors and pins attached to the arresters and working in the said slots; substantially as described and illustrated.

In testimony whereof I have hereunto set 80 my hand in the presence of two subscribing witnesses.

HENRY SIMPSON.
